UNITED STATES PATENT OFFICE.

JERE J. MURPHY, OF NAUGATUCK, CONNECTICUT, ASSIGNOR TO THE LASHER COMPANY, OF NAUGATUCK, CONNECTICUT, A CORPORATION OF CONNECTICUT.

DESIGN FOR A FREEZER DISPLAY CASE.

Application filed August 26, 1925. Serial No. 14,598. Term of patent 14 years.

To all whom it may concern:

Be it known that I, JERE J. MURPHY, a citizen of the United States, residing at Naugatuck, in the county of New Haven and State of Connecticut, have invented a new, original, and ornamental Design for Freezer Display Cases, of which the following is a specification, reference being had to the accompanying drawing, forming part thereof.

In this drawing: Fig. 1 is a front perspective view of the freezer display case. Fig. 2 is a rear perspective view of the same.

I claim:

The ornamental design for a freezer display case as shown.

JERE J. MURPHY.
